CIRCUIT FOR OPERATORS' TRANSMITTERS
AND RECEIVERS IN SERIES

John H. Voss, Rochester, N. Y., assignor to Automatic Electric Laboratories, Inc., Chicago, Ill., a corporation of Delaware

Application August 2, 1947, Serial No. 765,685

7 Claims. (Cl. 179—51)

1

This invention relates to telephone systems in general, but more particularly to circuits for operators' positions on manual switchboards which are used extensively in manual systems and for specific purposes in automatic systems.

The object of this invention is to provide a new and improved operators' telephone circuit arrangement, wherein the operators' jacks are wired in such a manner that a second operator's transmitter and receiver set may be plugged in and the two sets operated simultaneously with the two transmitters in series as well as the two receivers operating in series.

A further object of this invention is to provide a circuit arrangement wherein one common battery feed induction coil is associated with operators' jacks having switching controls for completing connections for either one of two operators' transmitter and receiver sets, to operate alone in the circuit or for completing connections for the operation of two operators' transmitter and receiver sets connected in series.

A further object is to operate two operators' transmitters in series on one common feed induction coil to reduce transmission loss.

It is common practice on manually operated switchboard positions to provide two sets of operators' jacks in order to facilitate changing from regular to relief operator without completely abandoning the particular position while the change is taking place and also such arrangements of jacks are necessary when new recruit operators are being trained. It has been common practice to wire the extra set of jacks in multiple with the regular operator's jack.

In the present embodiment the auxiliary set of twin jacks and the regular set of twin jacks are wired together in such a manner that one operator's transmitter and receiver set can be plugged into either twin jack and the operator's circuit will function correctly, or one such operator's transmitter and receiver set can be plugged into each twin jack and the switching arrangements provided are such that both sets function correctly with the two transmitters in series in the primary circuit of the induction coil and the two receivers in series in the secondary circuit of the same induction coil, resulting in a considerable reduction in transmission loss as compared with the operation of transmitters in multiple.

Fig. 1 shows a diagrammatic representation of the present invention; Fig. 2 shows the physical appearance of the twin plugs and jacks.

Fig. 1 shows two operators' transmitter and receiver sets, numbered 1 and 2 respectively. These

2

are of the usual type in which a four conductor twin plug, such as 9, is attached by a four conductor cord to a transmitter and receiver set, usually of the so called "breast-plate" type operator's set. It will be noted that the two conductors of the transmitter, of set No. 1, are wired to the tips 1 and 5 of the twin plug and that the two conductors of the receiver of the same operator's set are connected to the sleeves 2 and 6 of the twin plug 9. When this twin plug 9 is inserted in the adjacent, regular twin jack, tip 1 makes contact with tip 3 of the jack and tip 5 of the twin plug makes contact with tip 7 of the jack, also sleeve 2 of the twin plug 9 makes contact with sleeve 4 of the jack and plug sleeve 6 makes contact with sleeve 8 of the jack. In such a position a circuit can be traced from battery, lower winding of battery feed coil 61, lead 66, spring contact between springs 42 and 41 of the auxiliary jack, the make contact between springs 22 and 23 of the regular jack (as the plug is now in this jack), jack spring 26, tip 7 of the regular jack, tip 5 of plug 9, transmitter Number 1, tip 1 of plug 9 tip 3 of the regular jack, lead 67, the primary winding P, of the induction coil, upper winding of the battery feed coil 61, to ground.

Another circuit, the secondary circuit, can be traced from one side of the receiver (of set No. 1), sleeve 2 of the twin plug 9, sleeve 4 of the twin jack, spring 46, conductor 68, condenser 63, the S¹ portion of the secondary winding of the induction coil, condenser 64, lead 69, the contact of the auxiliary jack between springs 44 and 43, contact on the regular twin jack between springs 24 and 25 (as the plug is now in this jack) jack spring 27, sleeve 8 of jack, sleeve 6 of plug 9, to the other side of the receiver. It will be noted that the tip and ring of an outgoing circuit (not shown) are connected to their respective points in the secondary circuit and therefore an operator using an operator's set, such as set No. 1 plugged into the regular jack may transmit and receive over the outgoing circuit, the terminals being designated Tip and Ring.

Should plug 9 of operator's set No. 1 be removed from the regular jack and plug 59 of a similar operator's set, such as set No. 2, be inserted into the auxiliary twin jack, a circuit can be traced from battery, lower winding of battery feed coil 61, lead 66, jack spring 45, tip 57 of the auxiliary jack, tip 55 of the twin plug 59, transmitter No. 2, tip 51 of plug 59, tip 53 of the auxiliary jack, jack spring 35, contact between springs 32 and 31 (as the plug is now in this jack) contact between springs 11 and 12 of the

regular jack, lead 61, primary winding P of the induction coil, upper winding of battery feed coil 61, to ground. Another, the secondary circuit can be traced, from one side of receiver No. 2, sleeve 52 of plug 59, sleeve 54 of the auxiliary jack, jack spring 36, contact between springs 34 and 33, contact between springs 13 and 14 of the regular jack, lead 68, condenser 63, the S¹ portion of the secondary winding of the induction coil, condenser 64, lead 69, jack spring 46, jack sleeve 58, sleeve 56 of plug 59, to the other side of the receiver No. 2. The tip and ring terminals are connected to their respective points on the induction coil and the operators' circuit is now complete to the outside circuit (not shown). An operator using an operator's transmitter and receiver set, such as operator's set No. 2, plugged into the auxiliary jack may transmit and receive over the outgoing circuit.

Now we will give consideration to the conditions existing when two operators' transmitter and receiver sets are in use simultaneously on one common battery feed induction coil. First plug 9 shall be inserted into the regular jack and plug 59 inserted into the auxiliary jack. A circuit can be traced from battery, lower winding of battery feed coil 61, lead 66, jack spring 45, jack tip 57, plug tip 55, transmitter No. 2, plug tip 51, jack tip 53, jack spring 35, jack spring 26, jack tip 7 of the regular jack, plug tip 5, transmitter No. 1, plug tip 1, jack tip 3, jack spring 15, lead 67, primary winding P of the induction coil, upper winding of the battery feed coil 61, to ground. The secondary circuit can be traced from one side of the receiver No. 1, sleeve 2 of plug 9, sleeve 4 of the regular jack, lead 68, condenser 63, the S¹ portion of the secondary winding of the induction coil, condenser 64, lead 69, spring 46 of the auxiliary jack, sleeve 58 of jack, sleeve 56 of plug 59, receiver No. 2, plug sleeve 52, jack sleeve 54, jack spring 36, of the auxiliary jack, jack spring 27 of the regular jack, sleeve 8 of the regular jack, sleeve 6 of plug 9, to the other side of receiver No. 1.

As previously mentioned the tip and ring terminals of the operator's circuit may be connected to any outside circuit (not shown) and either an operator with set No. 1 or an operator with set No. 2 may transmit and receive over the outside circuit, or both simultaneous.

What is claimed is:

1. In an operator's telephone circuit, terminals for said circuit, an induction coil having a primary and a secondary winding, two sets of twin jacks and each of said twin jacks individually connected to said primary and said secondary windings, an operator's transmitter and receiver set terminating in a four conductor twin plug, comprising two plug tips and two plug sleeves, for transmitting telephone conversations and for receiving telephone conversations and other signals over the said terminals of said circuit responsive to said plug being inserted in one of said jacks, both of said sets of twin jacks equipped with switching springs, the switching springs of one of said twin jacks co-operating with the switching springs of said second twin jack when said four conductor twin plug is inserted in said one twin jack to short circuit the said second twin jack.

2. An operator's circuit as claimed in claim #1 in which the switching springs of said second twin jack co-operate with the switching springs of said one twin jack, when said four conductor

twin plug is inserted in said second twin jack, to short circuit the said one twin jack.

3. In an operator's telephone circuit, a first operator transmitter, a first operator plug having a pair of plug tip terminals, said first transmitter connected in series with said pair of plug tip terminals of said first plug, a first operator jack having a pair of jack tip terminals, a first pair of make springs and a first pair of break springs associated with said first jack, a second operator plug having a pair of plug tip terminals, said second transmitter connected in series with said pair of plug tip terminals of said second plug, a second operator jack having a pair of jack tip terminals, a second pair of make springs and a second pair of break springs associated with said second jack, a pair of talking conductors, the first of said talking conductors terminating in one of the jack tip terminals of said first jack and the second of said talking conductors terminating in one of the jack tip terminals of said second jack, a circuit for bridging said first transmitter across said pair of talking conductors including said plug tip terminals of said first plug, said jack tip terminals of said first jack, said first pair of make springs and said second pair of break springs completed in response to the operator plugging said first plug into said first jack; a second circuit for bridging said second transmitter across said pair of talking conductors including the plug tip terminals of said second plug, said jack tip terminals of said second jack, said second pair of make springs and said first pair of break springs completed in response to the operator first plugging said second plug into said second jack; and a third circuit for bridging said first and second transmitters in series across said pair of talking conductors including only the plug tip terminals of both said first and second plugs and the jack tip terminals of both said first and said second jacks in response to plugging both said plugs into said first and said second jacks.

4. An operator's telephone circuit as claimed in claim 3 wherein said first pair of make springs and said second pair of break springs in said first circuit close a short circuit across the jack tip terminals of said second jack, wherein said second pair of make springs and said first pair of break springs in said second circuit close a short circuit across the jack trip terminals of said first jack, and wherein both said first and said second break springs open said short circuits in response to plugging both said plugs into said first and said second jacks.

5. In an operator's telephone circuit, a first operator receiver, a first operator plug having a pair of plug sleeve terminals, said first receiver connected in series with said pair of plug sleeve terminals of said first plug, a first operator jack having a pair of jack sleeve terminals, a first pair of make springs and a first pair of break springs associated with said first jack, a second operator receiver, a second operator plug having a pair of plug sleeve terminals, said second receiver connected in series with said pair of plug sleeve terminals of said second plug, a second operator jack having a pair of jack sleeve terminals, a second pair of make springs and a second pair of break springs associated with said second jack, a pair of talking conductors, the first of said talking conductors terminating in one of the jack sleeve terminals of said first jack and the second of said talking conductors terminating in one of the jack sleeve terminals of said second jack; a

circuit for bridging said first receiver across said pair of talking conductors including said plug sleeve terminals of said first plug, said jack sleeve terminals of said first jack, said first pair of make springs and said second pair of break springs completed in response to the operator plugging said first plug into said first jack; a second circuit for bridging said second receiver across said pair of talking conductors including the plug sleeve terminals of said second plug, said jack sleeve terminals of said second plug, said second pair of make springs and said first pair of break springs completed in response to the operator first plugging said second plug into said second jack; and a third circuit for bridging said first and second receivers in series across said pair of talking conductors including only the plug sleeve terminals of both said first and second plugs and the jack sleeve terminals of both said first and second jacks in response to plugging both said plugs into said first and said second jacks.

6. An operator's telephone circuit as claimed in claim 5 wherein said first pair of make springs and said second pair of break springs in said first circuit close a short circuit across the jack sleeve terminals of said second jack, wherein said second pair of make springs and said first pair of break springs in second circuit close a short circuit across the jack sleeve terminals of said first jack, and wherein both said first and said second break springs open said short circuits in response to plugging both said plugs into said first and said second jacks.

7. In an operator's telephone circuit, first and second operators' headsets, plug and jack connections for said headsets, a pair of talking conductors, a first circuit for operatively connecting said first operator's headset to said talking conductors completed in response to the operator plugging said first headset into one of said jack connections, a second circuit for operatively connecting said second operator's headset to said talking conductors completed in response to the operator plugging said second headset into another of said jack connections, and a third circuit for operatively connecting said first and second headsets in series and to said talking conductors in response to the operator plugging said first and said second headsets, respectively, in said one and said another of said jack connections.
